UNITED STATES PATENT OFFICE.

WILLIAM GILMOUR, OF MONTREAL, QUEBEC, CANADA.

Brake-Shoe.

1,082,462.

Specification of Letters Patent.

Patented Dec. 23, 1913.

Application filed October 4, 1911. Serial No. 652,828.

To all whom it may concern:

Be it known that I, WILLIAM GILMOUR, of the city of Montreal, in the district of Montreal and Province of Quebec, Dominion 5 of Canada, have invented certain new and useful Improvements in Brake-Shoes; and I do hereby declare that the following is a full, clear, and exact description of the same.

My invention relates particularly to brake 10 shoes in connection with locomotives, railway and tramway cars, electric motors, and the like; and it has for its object to provide a device of this nature which will be more efficient and more durable than devices for 15 a like purpose heretofore known.

To this end the invention may be said to consist broadly of a brake shoe having a manganese lining particularly constructed to fit the carrier member and under normal 20 conditions be self retaining thereon.

For full comprehension, however, of my invention reference must be had to the accompanying drawings forming a part of this specification, in which similar reference 25 characters indicate the same parts, and wherein:

Figure 1 is a side elevation partly in sectional view of a brake shoe containing my invention, the section being taken on line 30 A A Fig. 2; Fig. 2 is an elevation of one half of the bearing face of my improved brake-shoe; Fig. 3 is a similar view to Fig. 2 of the back of one half of the shoe; Fig. 4 is a transverse sectional view taken on line 35 B B Fig. 1; Fig. 5 is an end view of the shoe; and Fig. 6 is a perspective view of one of the liners ready for application to the shoe body; Fig. 7 is a detail perspective view 40 of one of the liner-retaining faces of the shoe.

The carrier member or body of the shoe is indicated at *b* it being curved longitudinally to conform to the tread of the wheel, and formed with longitudinal side flanges *c* 45 to prevent outward lateral displacement of the liners the inward displacement of which is prevented by plane beveled faces *d d* and *e e* formed at opposite ends of the shoe body and a particular formation of the liners; while the flanges extend around the ends of the body and are provided with perforated lugs *g*.

The liners are similar in construction, each being formed from a blank consisting of a 50 strap *k* of manganese steel, or other manganese metal, the ends of which are re-

duced in thickness at one face to produce relatively thin ends, *m*, the continuity of the flatness of the other face being unbroken throughout its length. These straps are 60 preferably each equal in width to approximately one third the width of the shoe body between its flanges *c*, and the beveled faces *d d* and *e e* of such shoe body are of corresponding width.

To prevent inward displacement of the liner or complete removal of the liner from the shoe, the ends of the shoe are provided with beveled surfaces, *D*, said surfaces being beveled or inclined in two directions. Inward displacement is prevented by beveling these surfaces *D* with respect to the ends of the shoe as shown by the converging edges *d* of said surfaces. In addition to this inclination of the faces *D*, they incline inwardly with respect to the inner face of the shoe "*b*", as shown by the location of the opposite edges, *e*, of said surfaces *D*. The wedging or dovetail action thus obtained by providing surfaces beveled with respect to 70 the ends and to the face of the shoe-body holds the liners firmly in operative position.

In order to facilitate the assembling of the parts of my improved shoe, the liners 85 are preferably supplied to the trade with the ends *m* extending substantially at right angles to the main length as indicated by dotted lines *m* (Fig. 6) to which position they are preferably bent and the main 90 length *k* is curved to conform to the face of the shoe body it is intended to fit. This bending is preferably done as follows: The liners thus partially formed are heated and placed upon a die corresponding in form to 95 the front or wheel side of, and approximately two per cent. (2%) longer than, the shoe body (see Fig. 2) and, while hot, pressed and thereby have imparted thereto the curvature of the body (see Fig. 1), with 100 their ends bent to the dotted positions shown at *m* Fig. 6. After being thus formed the liners are ready to be fitted upon the shoe body and after being set and clamped rigidly in place these ends are pressed inwardly while cold and thereby made to 105 clasp the beveled faces *d d* and *e e*.

When the ends *m* are pressed to tightly clasp these beveled faces the liners will be held against relatively inward displacement 110 by what may be termed the circumferential angle of inclination indicated in Figs. 2

2
and 3, and against radial displacement by what may be termed the tangential angle of inclination shown in Fig. 1.

In order to prevent the parts of each liner 5 when worn through from falling upon the track split cotter pins r , or other suitable devices, are carried in the perforated lugs g and project across the ends m .

I have discovered that manganesean friction faces of brake shoes have greater braking efficiency and proportionately greater durability than the material of any brake shoes heretofore known, and in consequence have devised a means whereby the alloy 15 manganese-steel is applied commercially to this use.

What I claim is as follows:—

1. A brake-shoe comprising a carrier-member having a flange at one side, such member having beveled surfaces contiguous to the flange and beveled inwardly with respect to the ends and inwardly with respect to the inner face of the shoe and a liner consisting of a strap upon the said 20 member and retained against lateral displacement in one direction by the said flange and against displacement in the opposite direction or complete displacement from the shoe by the beveled surfaces.
2. A brake-shoe comprising a carrier-member having each end formed with a pair of spaced faces each beveled in two directions, and such member having side flanges; 25

and spaced liners consisting of straps clasping the said beveled faces.

35

3. A brake-shoe comprising a carrier-member having each end formed with a pair of spaced faces each beveled in two directions, and such member having side flanges; and spaced liners consisting of straps with 40 relatively thin ends clasping the said beveled faces.

4. A brake-shoe comprising a carrier member having each end formed with a pair of spaced faces each beveled in two directions, and such member having side flanges; and a pair of spaced liners consisting of manganese-steel straps with relatively thin 45 ends clasping the said beveled faces.

5. A brake-shoe comprising a carrier-member having each end formed with a pair of spaced faces each beveled in two directions, and such member having side flanges; a pair of spaced liners consisting of manganese-steel straps with relatively thin ends 50 clasping the said beveled faces, perforated lugs projecting from the flanges; and retaining devices carried by the said lugs.

50

55

In testimony whereof I have signed my name to this specification in the presence of 6 two witnesses.

Montreal September 26 1911.

WILLIAM GILMOUR.
